CLAIM

The ornamental design for a rail for fastening a cover to a canopy, as shown and described.

DESCRIPTION

FIG. 1 is an end elevational view of a rail for fastening a cover to a canopy, illustrating my new design;

FIG. 2 is a left side elevational view thereof, the rail being broken away to indicate indeterminate length;

FIG. 3 is a right side elevational view thereof, the rail being broken away to indicate indeterminate length;

FIG. 4 is a top plan view thereof, the rail being broken away to indicate indeterminate length; and,

FIG. 5 is a bottom plan view thereof, the rail being broken away to indicate indeterminate length.
